(57) **CLAIM**

The ornamental design for a bottle cap, as shown and described.

DESCRIPTION

FIG. 1 is a top perspective view of a bottle cap according to the present invention;

FIG. 2 is a side view of the bottle cap of FIG. 1;

FIG. 3 is a bottom perspective view of the bottle cap of FIG. 1;

FIG. 4 is another bottom perspective view of the bottle cap of FIG. 1;

FIG. 5 is a top view of the bottle cap of FIG. 1;

FIG. 6 is a bottom view of the bottle cap of FIG. 1.

FIG. 7 is another bottom perspective view of the bottle cap of FIG. 1, shown in use with a sealing disk;

FIG. 8 is another bottom perspective view of the bottle cap of FIG. 1, with the sealing disk; and,

FIG. 9 is a bottom view of the bottle cap of FIG. 1 with the sealing disk.

Only one side view is presented as other side views are identical.

The Vero logo shown in the drawings is a registered trademark of Vero Water Inc. and forms no part of the claimed design.
